V. WILLIAMS.
WIRE TIGHTENING AND SPLICING TOOL.
APPLICATION FILED JUNE 16, 1914.

Patented Nov. 21, 1916.

UNITED STATES PATENT OFFICE.

WILLIAM WILLIAMS, OF CHESTER, CALIFORNIA.

WIRE TIGHTENING AND SPLICING TOOL.

1,205,832.

Specification of Letters Patent. Patented Nov. 21, 1916.

Application filed June 16, 1914. Serial No. 845,441.

To all whom it may concern:

Be it known that I, WILLIAM WILLIAMS, a citizen of the United States, residing at Chester, in the county of Plumas, State of California, have invented certain new and useful Improvements in Wire Tightening and Splicing Tools; and I do hereby declare the following to be a full, clear, and exact description of the invention, such as will enable others skilled in the art to which it appertains to make and use the same.

This invention relates to certain novel and useful improvements in a tool adapted particularly for use in tightening and splicing telephone, telegraph, fence wires and the like.

In carrying out my invention it is my purpose to provide a tool through the medium of which strands of wire to be joined may be properly stretched to take up any undesirable slack and the ends of said wire brought into position for splicing.

Still a further object of my invention is the provision of a tool of this class which will embody in its construction the desired features of simplicity, efficiency and reliability and which may be manufactured and marketed at a relatively low cost.

Furthermore I propose to provide a tool of this class which may be readily applied to and removed from its operative position, and which may be easily manipulated to quickly perform the functions for which it is intended.

With the above recited objects and others of a similar nature in view, my invention consists in the construction, combination and arrangement of parts set forth in and falling within the scope of the appended claim.

In the accompanying drawings: Figure 1 is a top plan view showing the tool in position ready to stretch the ends of the wire to be joined. Fig. 2 is a similar view showing the tool in the position it occupies after the ends have been stretched and the tool turned to twist or overlap the ends of the wire. Fig. 3 is a cross sectional view taken through the locking cam of the tool taken on the line 3—3 of Fig. 1, Fig. 4 is a similar view taken on the line 4—4 of Fig. 1, Fig. 5 is a view showing the manner of employing the tool to make the splice shown in Fig. 6, and Fig. 6 is a detail view of another form of splice made with my improved device.

In the present instance my tool comprises

two parts, a clamping section indicated as an entirety by the letter A and a crank section which is designated as a whole by the letter B, and which is adapted to be connected with the clamping section as is shown in Fig. 1. This clamping section A embodies a bar-like body portion 1 of iron or other suitable material, one end of which is formed with an enlarged eye or bore 2, through which the crank is inserted. Adjacent this enlarged eye I provide a horn 3 which extends at right angles to the bar 1 and which forms a guide and bearing for one of the wire strands. The opposite end of the clamping member A is formed with an upturned arm 4 having an angular or lateral end 5 in which is journaled the pivot bolt 6 of the eccentric or cam 7, the bearing or gripping face of the cam being corrugated as at 8. The handle for operating the cam to bring it into and out of wire gripping position is shown at 9. It is to be noted that when the end of the wire is to be gripped by the cam the latter is turned to its locked position and the wire gripped between the corrugated or gripping face of the cam and the adjacent side 10 of the arm 4. The numeral 11 designates a second horn which extends in the same direction as the arm 4, and is spaced apart therefrom as shown in Figs. 1 and 3, this horn being arranged on the opposite side of the bar 1 from the horn 3.

The crank portion B of the tool is formed at one end with a handle or gripping section 12 and at its opposite end terminates in a shank 13 which is adapted to be inserted through the eye 2 of the clamp member, this shank 13 having a bore or hole 14 extending therethrough through which the end of a wire strand may be passed, while 15 indicates a collar at the inner end of the shank member, which collar forms an abutment or stop for limiting the movement of the shank through the eye in one direction.

The above is a description of the mechanical features of my invention, and the manner of using the same will be readily understood by reference to Figs. 1 and 2 wherein I have shown the tool as employed in stretching and splicing the ends of two strands of wire. One of the strands is indicated at W, while the other strand is shown at W'. In using the tool the crank portion thereof is connected with the clamping part as shown in Fig. 1, and one of the wires, for

instance, the wire W, runs between the shank section 13 and the horn 3 and has its terminal clamped by the eccentric cam 7, as will be readily understood. The opposite 5 wire W' is passed between the spur 11 and the arm 4, and has its terminal inserted in the hole 14 of the shank 13, a wrap or so being taken to insure that the end of the wire will not slip. The device is now ready 10 for tightening the strands of wire to take up slack as shown in Fig. 1, and this tightening is accomplished by turning the crank handle 12, which results in drawing the wire strands as will be readily understood. 15 When the strands have been sufficiently tightened the tool is tilted or canted, as shown in Fig. 2, to make a complete wrap of one wire about the other as shown at W'' and is then rotated with the wires as an axis 20 to coil the end of each strand about itself. To effect the splice shown in Fig. 6, the tool is employed merely as a tightener to draw taut in overlapping relation the broken ends of a wire, and is then tilted or canted to partially 25 twist the wires as shown in Fig. 5. A pair of ordinary pliers is now employed to hold the wrapped strands at their point of connection, the pliers being held with one hand while the operator removes the 30 tool with the other hand. A splicing tool, not shown, is then employed to coil the end of each strand forward about the opposite strand and the splice is complete.

From the above description taken in connection with the accompanying drawings,

it will be observed that I have provided an exceedingly simple yet efficient tool for use in tightening and splicing wires, and said tool will be found particularly advantageous for farmers, linemen, and others.

40

While I have herein shown and described one particular embodiment of my invention, I wish it to be understood that I do not confine myself to all the precise details of construction herein set forth by way of 45 illustration, as modification and variation may be made without departing from the spirit of the invention or exceeding the scope of the appended claim.

50

What I claim is:—

A tool of the class described comprising a body member having a bearing portion at one end, a lateral extension at the other end of the body member, means carried by and coöperating with the extension to clampingly engage a wire, a second extension in close relation to the first extension, a crank member including a shank rotatably mounted in the bearing and adapted to engage a wire, and a lateral extension on the body adjacent the shank, said shank and extensions being substantially parallel one to the other.

55

In testimony whereof, I affix my signature, in the presence of two witnesses.

WILLIAM WILLIAMS.

Witnesses:

HARVEY WILLIAMS,
EDGAR C. OLSEN.
